UNITED STATES PATENT OFFICE.

JULIUS J. RAUH, OF NEW YORK, N. Y.

SELF-CLEANING COMB.

No. 936,766.

Specification of Letters Patent.

Patented July 6, 1908.

Application filed December 22, 1908. Serial No. 468,795.

To all whom it may concern:

Be it known that I, JULIUS J. RAUH, citizen of the United States, residing in New York, in the county of New York and State 5 of New York, have invented certain new and useful Improvements in Self-Cleaning Combs, of which the following is a specification.

The present invention relates to improvements in combs, and more particularly to a 10 novel attachment which is designed to be applied to the comb for removing accumulations of dirt from between the teeth thereof, thereby permitting of the comb being readily maintained in a clean and sanitary condition.

15 The invention further contemplates an attachment of this character which is inexpensive in its construction, which can be permanently applied to the comb and will not in any manner interfere with the use 20 thereof, and which can be readily manipulated at any time to remove the accumulations of dirt from between the teeth of the comb.

For a full understanding of the invention 25 and the merits thereof and also to acquire a knowledge of the details of construction and the means for effecting the result, reference is to be had to the following description and accompanying drawings, in which:

30 Figure 1 is a perspective view of a comb provided with a cleaning attachment constructed in accordance with the invention, the said attachment being shown in the position assumed when not in use, Fig. 2 is a 35 similar view showing the attachment in the position assumed when it has been moved outwardly to remove the accumulations of dirt from between the teeth of the comb, Fig. 3 is a transverse sectional view through the comb 40 with the cleaning attachment in the position shown in Fig. 1, and, Fig. 4 is a similar view with the cleaning attachment in the position shown in Fig. 2.

Corresponding and like parts are referred 45 to in the following description and indicated in all the views of the drawings by the same reference characters.

Referring to the drawing, the numeral 1 50 designates a comb which may be formed of any suitable material and is provided along one of its longitudinal edges with the usual teeth 1^a. Opposite ends of the comb are formed with the transverse slots 2 and the walls between adjacent teeth at the base 55 thereof are inclined from one side of the comb to the opposite side as indicated at 3.

Slidably mounted upon one side of the comb is a plate 4 and projecting from this plate is a series of cleaning fingers 5 the extremities of which are deflected inwardly at 5^a so as to 60 be received between the teeth 1^a of the comb. The ends of the plate 4 are bent around opposite ends of the comb at 4^a so as to guide the plate as it is moved laterally upon the comb. It will also be observed that the end 65 portions of the plate are provided with projections 6 which operate within the respective slots 2 and engage opposite ends of the slots to limit the sliding movement of the plate. The intermediate portion of the 70 plate is provided with a finger piece 7 which projects toward the back of the comb and is curved outwardly to permit of a firm grip being readily obtained thereon. The portions of the plate 4 upon opposite sides of this finger piece are provided with slits which extend inwardly from the rear edge thereof and form the spring tongues 8. These spring 75 tongues frictionally engage the comb to hold the plate against rattling and when the plate is moved upwardly so as to hold the fingers in an inoperative position, these spring tongues engage a depression 9 in the side of the comb and hold the plate against movement. When it is desired to clean the comb, 80 it is merely necessary to grasp the finger piece 7 and move the plate downwardly into the position shown in Fig. 2, the cleaning fingers 5 being thereby caused to travel outwardly between the teeth 1^a so as to remove 85 any accumulations of dirt therefrom. After the comb has been cleaned the plate 4 is moved backwardly into the position shown in Fig. 1 with the spring tongues 8 in engagement with the depression 9 and the inwardly 90 deflected ends 5^a of the fingers 5 fitting against the inclined walls 3 at the base of the teeth.

Having thus described the invention, what is claimed as new is:

1. A device as specified comprising a comb having an inclined wall formed at one side adjacent the upper edge of the same and laterally formed slots disposed in said side, a plate positioned against said side of said comb, 105 curved ends formed on said plate for engagement about the opposite ends of said comb to retain the plate in position, projections formed on said plate for engagement in the transverse slots formed on said comb, tongues 110 disposed in the upper edge of said plate for engagement against the inclined face formed

thereon and a plurality of fingers depended from said plate for engagement between the teeth of said comb.

2. A device as specified comprising a comb having transverse slots formed in the opposite ends of the same in one side thereof, an inclined face formed in said side of said comb adjacent the upper edge thereof, a plate slidably disposed against said side of said comb, 5 tongues carried by said plate for frictional engagement against said comb, projections carried by said plate for engagement in said

transverse slots to limit the movement of said plate, beveled edges formed on said comb between the teeth thereof and fingers 15 depended from said plate and adapted to engage against said inclined faces.

In testimony whereof I affix my signature in presence of two witnesses.

JULIUS J. RAUH. [L. s.]
